UNITED STATES PATENT OFFICE

140,847

DESIGN FOR LEATHER OR THE LIKE

Bessie Casso, Boston, Mass., assignor to Matilda Silver, doing business as Sufix Manufacturing Co., Boston, Mass.

Application October 14, 1944, Serial No. 115,761

Term of patent 7 years

(Cl. D87—3)

To all whom it may concern:

Be it known that I, Bessie Casso, a citizen of the United States residing at Boston, in the county of Suffolk and State of Massachusetts, have invented a new, original, and ornamental Design for Leather or the like, of which the following is a specification, reference being had to the accompanying drawing, forming part thereof.

The drawing is a plan view of a piece of leather or the like. The dotted lines outline a design unit which is repeated over the leather as indicated.

I claim:

The ornamental design for leather or the like, substantially as shown and described.

BESSIE CASSO.
